(57) **CLAIM**

The ornamental design for a fan heater, as shown and described.

DESCRIPTION

FIG. 1 is a front perspective view of a fan heater showing my design.

FIG. 2 is a rear perspective view of the fan heater in FIG. 1.

FIG. 3 is a front elevation view of the fan heater in FIG. 1.

FIG. 4 is a rear elevation view of the fan heater in FIG. 1.

FIG. 5 is a left side elevation view of the fan heater in FIG. 1.

FIG. 6 is a right side elevation view of the fan heater in FIG. 1.

FIG. 7 is a top plan view of the fan heater in FIG. 1; and, FIG. 8 is a bottom plan view of the fan heater in FIG. 1. The broken lines in the drawings are employed to show unclaimed portions of the fan heater, and form no part of the claimed design.
